CLAIM

The ornamental design for sportswear with attached towel and water bottle, as shown and described.

DESCRIPTION

FIG. 1 is a perspective view of a sportswear with attached towel and water bottle, showing my new design;

FIG. 2 is a front elevational view of the invention;

FIG. 3 is a rear elevational view of the invention;

FIG. 4 is a left-side elevational view of the invention;

FIG. 5 is a right-side elevational view of the invention;

FIG. 6 is a top plan view of the invention; and,

FIG. 7 is a bottom plan view of the invention.

The broken lines showing a water bottle in FIG. 1 are included for the purpose of illustrating the invention in use, and form no part of the claimed design.

The broken lines on the surface of the garment, shown in FIGS. 1 and 3-7, represent stitching.
